UNITED STATES PATENT OFFICE.

GEORGE M. JOHNSON, OF JEANNETTE, PENNSYLVANIA, ASSIGNOR TO FORT PITT MINE EQUIPMENT COMPANY, OF PITTSBURGH, PENNSYLVANIA, A CORPORATION OF PENNSYLVANIA.

CAR-RETAINING DEVICE.

Application filed September 15, 1926. Serial No. 135,568.

My invention relates to car transfer apparatus, and particularly to those of the chain rail conveyer type, wherein chain links are provided with rail sections upon which the 5 flanged wheels of a car may be supported and the car transferred from one position to another.

This invention constitutes an improvement upon that disclosed in my application, 10 Serial No. 733,528, filed August 22, 1924, and is more especially directed to an improved form of stop for preventing backward movement of cars or locomotives upon an inclined conveyer independently of movement of the conveyer.

My invention has for its object the provision of an improved form of stop which will effectively prevent movement of the cars down an inclined conveyer, independently 20 of movement of the conveyer, either when the conveyer is employed to transfer the cars from a track at a lower level to another track in a higher plane, or to lower cars from the higher track to the lower track, 25 while at the same time, the stops will be automatically moved to inoperative position to permit passage of a locomotive, for instance, upwardly along the conveyer, independently of traveling movement of the conveyer, as when the locomotive brings a load 30 of cars to the lower end of the conveyer and it is desired to move the same out of the path of the cars to permit their being fed forward by the conveyer.

Another object of my invention is to provide means for automatically moving the stop horns to inoperative position when they pass from the upper flight of the conveyer to the lower flight thereof, so that less head 35 room will be required for the apparatus, since the horns will not be permitted to project below the lower chain flights.

Still another object of my invention is to simplify and improve generally the structure and operation of transfer apparatus.

One form which my invention may take is shown in the accompanying drawing wherein Figure 1 is a side elevational view of chain rail apparatus embodying my invention; Fig. 2 is a view taken on the line II-II of Fig. 1; Fig. 3 is a plan view, on an enlarged scale, of a portion of the apparatus of Fig. 1; Fig. 4 is a side elevational view of the apparatus of Fig. 3, and Fig. 5 is a

side elevational view showing the position 55 occupied by the horns when traveling along the lower chain flight.

The drawings show a chain rail conveyer for transferring cars 6 from tracks 7 in one plane to tracks 8 in a higher plane. The 60 conveyer is mounted on a framework 9 in which are journaled shafts 10 and 10^a. The shaft 10^a is driven from a suitable source of power (not shown). Two sprocket wheel devices 11 are mounted upon each of the 65 shafts and each sprocket wheel device is provided with a pair of discs 12 that have recesses for the reception of rollers 13. The rollers 13 are mounted on the ends of shafts 14 that serve as pintles or hinge pins for 70 chain links 15 and 16. Rotation of the shaft 10^a therefore imparts traveling movement to the chains. A pair of channel irons 17 (Fig. 2) are provided for the upper flight of each of the chains to afford vertical support for 75 the rollers 13 and to hold the chains against lateral movement, so that the cars will not become derailed when being transported by the conveyer.

Each of the chain links 15-16 is provided 80 with a rail head portion, as shown more clearly in Fig. 2, that cooperate to form a substantially continuous track for cars when passing along the upper chain flight. Rails 7 and 8 extend along the conveyer for some distance beyond the sprocket wheels 11 and are of suitable form to permit the cars to pass therefrom to the chain rails that are formed by the links 15 and 16.

Each link 16 has a portion cut away, as 90 shown more clearly in Figs. 3, 4 and 5, for the reception of a horn or stop lug 18 that is pivotally connected to the link 16 by means of a bolt or shaft 19. A weighted member 20, which is of greater weight than 95 the lug 18, is pivotally connected to the link 16 by means of a shaft member 21. The members 18 and 20 are each provided with gear teeth that intermesh, as shown more clearly in Figs. 4 and 5.

When the links 16 enter the upper conveyer flight, the weights 20 will swing in a counter-clockwise direction, from the position indicated in dotted lines in Fig. 4 to that indicated by full lines, thus moving the 105 stops 18 in a clockwise direction about their pivots, and into position to engage the treads of the car wheels and causing the cars to be

advanced with the conveyer. The stops 18, when in raised position, seat against the shoulder portions 16^a of the links 16.

When the links 16 are about to enter the 5 lower flights of the chains, the weights 20 are swung by the action of gravity from the position shown in Fig. 4 to that shown in Fig. 5, thus moving the horns 18 into the recesses or cut out portions of the links 16, so 10 that they do not project beyond the lower portion of the framework, and it is therefore unnecessary to provide clearance beneath the framework for the horns. Channel irons 22 are provided to maintain the lower chain 15 flights in properly alined position and prevent sagging and swaying thereof.

While the weights 20 automatically move the stop horns 18 to operative and inoperative positions, they do not prevent movement 20 of the horns to depressed position, as when it is desired to drive a locomotive across the conveyer, from the lower end to the upper end thereof, nor cause derailment of a car which may happen to be advanced from the 25 tracks 7 against the rear sides of the horns 18, since the horns will fold forwardly and permit the wheels to pass over the same. Furthermore, the horns 18, when folded down, function as rail heads to assist in 30 supporting the weight of a locomotive which is being driven over the conveyer independently of the conveyer movement.

Instead of providing but one weight upon each of the shafts 21, a smaller weight can 35 be secured to each end of the shafts, thus reducing the amount of clearance necessary for the weights.

I claim as my invention.

1. The combination with a conveyer composed of chain links having rail head portions for supporting cars, of a pivoted stop member carried by one of said links, means for holding said stop member in position to prevent movement of cars in one direction 40 relative to the conveyer, and means yieldable to permit movement of the stop to inoperative position by cars moving in the opposite direction.

2. The combination with a conveyer composed of chain links, one of which has a 50 cut-out portion, of a stop member supported in said cut-out portion, and means carried by the conveyer for yieldably holding said stop member in protruded position relative 55 to said cut-out portion, during its travel along one conveyer flight and for moving it to retracted position during travel along another flight.

3. The combination with a conveyer composed of chain links, of a stop member and a weight pivotally connected to one of said links, the weight and stop member being relatively movable and so interconnected 60 that the stop member will be yieldably held 65 by the weight in extended position.

4. The combination with a conveyer composed of chain links, of a stop member and a weight pivotally connected to one of said links, the weight and stop member being relatively movable and so interconnected that 70 the stop member will be swung to operative position during passage of said link along one flight of the chain, and will be swung to inoperative position when the link passes from said flight.

5. The combination with a conveyer composed of chain links, of a stop member pivotally connected to one side of one of the links, and means carried by the conveyer for yieldably holding said stop member extended at right angles to said link, when the link 80 is in one portion of its path of travel and for moving said member into parallelism with the link when said link is at another point in its path of travel.

6. The combination with a conveyer composed of chain links, of a stop member pivotally supported by one of the links, a weighted member pivotally connected to said link, the said stop member and weighted 90 member being provided with interengaging teeth whereby the stop member will be yieldably held in a predetermined position.

7. The combination with a conveyer, composed of chain links having rail head portions for supporting cars, the head portion of one link being partially cut away, of a stop member pivotally supported in said cut away portion, the said member being movable from a position at right angles to the 100 link, to a position in parallelism therewith.

8. The combination with a conveyer composed of chain links having rail head portions for supporting cars, the head portion of one link being partially cut away, of a 105 stop member pivotally supported in said cut away portion, the said member being movable from a position at right angles to the link, to a position in parallelism therewith, and one surface of the stop member lying 110 in the same plane as the rail head portion of the link and serving to assist in supporting the wheels of cars passing over said link, when the stop member is in depressed position.

9. The combination with a conveyer composed of chain links having rail head portions for supporting cars, one of said links having its head portion of reduced width, of a stop member pivotally connected to the 120 conveyer and movable from a position at right angles to said link into parallelism with the upper surface of the said link and when in folded position, functioning as a rail head to assist in supporting the weight 125 of a vehicle.

In testimony whereof I the said GEORGE M. JOHNSON have hereunto set my hand.

GEORGE M. JOHNSON.
